UNITED STATES PATENT OFFICE.

AUGUST J. HANKE, OF CHICAGO, ILLINOIS.

FLOOR MOP.

Application filed March 31, 1922. Serial No. 548,339.

To all whom it may concern:

Be it known that I, AUGUST J. HANKE, a citizen of the United States, residing at Chicago, in the county of Cook and State of Illinois, have invented a certain new and useful Improvement in Floor Mops, of which the following is a full, clear, concise, and exact description, reference being had to the accompanying drawings, forming a part of this specification.

The invention relates to floor mops such as are ordinarily used in washing or dusting floors in homes, offices, stores and other places.

15 The prime object of the invention is to provide a simple and inexpensive holder for the mop proper, i. e., the mop cloth or mop yarn, hereinafter called mop, which holder may be punched, stamped, or otherwise formed into the desired shape and constructed of relatively light material, yet will be strong enough to successfully withstand the various strains which will be applied to it when it is in use.

25 It is a further object of the invention to provide a construction whereby the mop can be quickly and readily inserted in the holder, and can be as quickly and readily removed therefrom.

30 It is an additional object of the invention to provide a lock of simple construction for securing the clamping arms of the holder and the mop in locked relation to each other, and to prevent their becoming accidentally unlocked and permitting the mop to be loosened or released during use.

It is an object of the invention to provide a lock, a portion of which is arranged at an angle, or at one side of the center of 40 the locking element, when said element is arranged in locked relation to the other parts of the structure and is in its normal operative position, so that gravity may act and assist in maintaining the locking element and the mop in locked relation and prevent the separation of the clamping arms of the mop holder and the mop.

It is a further object of the invention to provide a means which will cooperate with 50 the locking element and maintain the locking element in its locked relation.

It is a further object of the invention to provide a simple hinge connection between the clamping arms of the mop holder.

55 It is a further object of the invention to arrange the clamping arms of the holder so

that one arm is hinged to and swings away from the other in a plane longitudinal of the mop stick, as distinguished from an arm which is pivoted to and swings away from the other arm in a plane transverse of the mop stick.

In the embodiment of the invention illustrated, the mop holder is composed of the usual handle, or mop stick, clamping arms and supporting braces. The mop stick has secured thereto a fixed clamping arm. From adjacent the ends of the fixed clamping arm the supporting braces extend to the mop stick and are secured to the handle. These braces are secured to the handle by means of bolts and nuts, or other fastening means. Each of the supporting braces secured to the handle by means of bolts and nuts is provided with a curved portion for closely engaging the mop stick, which is usually round. An additional or swinging clamping arm is arranged in association with the fixed clamping arm. One end of the fixed clamping arm is provided with one part of a hinge, and the other end of the fixed clamping arm is provided with a means for engaging the locking element. One end of the swinging clamping arm is provided with the other part of the hinge, and the other end of the swinging clamping arm is provided with the locking element referred to. The locking element includes a ring of a certain shape and configuration, which ring is employed to releasably lock the ends of the fixed clamping arm and the swinging clamping arm, respectively.

The hinge connection between the fixed clamping arm and the swinging clamping arm permits the latter to be swung at the hinge in a plane longitudinal of the mop stick, allowing the mop to be arranged and clamped in the holder between the fixed and swinging clamping arms, or to be removed therefrom when this is found necessary or desirable.

The end of the fixed clamping arm away from the hinged end is notched on both sides of the arm adjacent the extremity thereof. The notches are arranged relatively to the end of the fixed arm so that the ring which engages the notches is held at an angle to the vertical when the ring is arranged to lock the two clamping arms against separation.

110 The locking ring is adapted to be passed over the end of the arm having the notches,

to thereby allow the ring to be arranged to lock the two clamping arms together. To accomplish this, one part of the ring is constructed of a sufficient dimension or diameter to allow it to be passed over the end of the arm to which it is to be locked. The locking ring is also constructed to provide another portion of a smaller diameter, which engages the end of the arm in the notches and prevents the separation of the clamping arms after the mop has been inserted between the arms, yet permits the locking element to be readily released and the mop readily removed and replaced when this is desired.

The ends of the arms as assembled are constructed so that curved surfaces and edges are presented, thus making it easier to handle the mop, since it will not catch so readily in these round edges as it would were they sharp and angular. In addition, the rounded edges will lessen the possibility of scratching and marring the woodwork and furniture when the mop is being used.

The invention will be described and more readily understood when read in conjunction with the accompanying drawings forming a part hereof, which illustrate one embodiment of which the invention is susceptible, it being obvious that changes and modifications may be made without departing from the spirit of the appended claims forming a part hereof.

In the drawings,

Fig. 1 is a front elevation of a mop holder constructed according to the invention and showing it applied to a mop stick and engaging the mop;

Fig. 2 is an enlarged end view of the structure shown in Fig. 1;

Fig. 3 is a top plan view of a portion of the structure;

Fig. 4 is a section taken on line 4--4 of Fig. 2; and

Fig. 5 is an end view of the hinged end of the mop holder illustrated in Figs. 1, 2 and 4.

The structure of the invention comprises the usual handle or mop stick 10, a pair of metallic angle supporting braces 11 and 12, the metallic fixed clamping arm, generally designated 13, the metallic swinging arm generally designated 14, and the locking element generally designated 15.

The supporting braces 11 and 12 are secured to, and are held with relation to, the mop stick or handle 10 by means of the bolts and nuts 16 and 17. The bolts are passed through the curved portions 18 and 19 of the supporting braces 11 and 12, respectively, and also through the mop stick 10. The supporting braces 11 and 12 are provided with the bent ends 20 and 21, which are secured to the outer ends of the fixed clamping arm 13 by rivets, as shown, or in some other

suitable manner. The fixed clamping arm is secured to the end of the mop stick 10 by a nail, screw, or other means, 22 passing through the arm 13 and into the end of the mop stick 10. The supporting braces 11 and 12 provide the proper strength and rigidity to the mop holder and prevent the clamping arms from being bent by the various strains applied to them during the mopping operation.

One of the ends of the fixed clamping arm 13 is recessed or cut away as at 23, and the material at the opposite sides of the cut away portion is bent upon itself to provide the loops or knuckle 24. The knuckle 24 provides one part of the hinge structure whereby the swinging clamping arm 14 may be swung in a plane longitudinal of the mop stick to engage and release the mop 25 when released by the locking element 15.

The end of the swinging clamping arm 14 adjacent the knuckle 24 is formed with the pintle portion 26 and the neck 27. The opposite ends of the pintle 26 are arranged within the loops or knuckle 24 of the fixed clamping arm 13, and thus complete the hinge connection whereby the swinging clamping arm 14 may be swung toward and away from the fixed clamping arm to allow the mop to be associated with, or removed from, the clamping arms.

The swinging clamping arm 14 is bent at right angles adjacent the hinged end as indicated at 28, providing the portions 29 and 30. This construction enables the swinging clamping arm 14 to be held in spaced relation to the fixed clamping arm 13 and provides a space for the reception of the mop, which is normally arranged between the fixed and swinging clamping arms of the mop holder.

The end of the swinging clamping arm 14 away from the hinge connection is looped as indicated at 31, and has pivotally secured thereto the locking element or ring 15. The ring 15 is preferably formed of a certain configuration, as shown in the drawings. It is provided with the straight portion 32, which is journaled in the loop 31. The ring is also formed with the straight parallel side portions 33 and 34 and the arc portion 35.

The distance between the straight parallel side portions 33 and 34 of the locking element 15 is of a slightly greater dimension than the width of the fixed clamping arm 13. Thus, when the adjacent end of the swinging clamping arm 14 is moved toward the fixed clamping arm 13, the locking element or ring 15 may be passed over the end of the fixed clamping arm 13 into engagement therewith, and may be moved to cause the disconnection and disassociation of the locking ring 15 in a similar manner.

The side edges of the end of the fixed clamping arm 13 adjacent the locking ele-

ment or ring 15 are provided with the notches 36 and 37, which cooperate with the arc portion 35 of the locking ring 15 to prevent the locking ring 15 from moving from its inwardly inclined position, in which position it is maintained to lock the mop within the clamping arms. The extremity of the fixed clamping arm adjacent the notches 36 and 37 is bent and turned on itself to form a rounded end and a transverse strengthening rib 38. The rib 38 also cooperates with the notches 36 and 37 to maintain the parts in locked relation during the mopping operation.

By referring to Figs. 1, 3 and 4, it will be noted that when the various parts of the mop holder are in normal operative position the locking element 15 is arranged at an angle to the vertical, or in other words, it is inclined inwardly. Thus, if the swinging clamping arm 14 is moved toward the fixed clamping arm 13 during the mopping operation, the force of gravity moves the locking element or ring 15 inwardly toward the mop stick, which maintains the necessary locked relation of the fixed and swinging clamping arms, and thus the accidental separation of the clamping arms and the accidental removal of the mop is prevented. The tendency of the ring 15 in the construction shown and described, when pressure is exerted on the swinging clamping arm, is to move the ring 15 in an upward and inward direction in the notches 36 and 37. The weight of the ring 15 causes it, after it has moved its limit in the notches, to fall inwardly and on the fixed clamping arm 13 or on the bent end 20 of the reinforcing and supporting brace bar 11. When the pressure is released from the swinging clamping arm 14, the swinging clamping arm draws the locking ring 15 downwardly in the notches 36 and 37, so that the end of the arc portion 35 of the ring is drawn away from its inward resting place against the fixed clamping arm or the bent end 20, to a position of rest in the notches 36 and 37. As stated, the bent strengthening rib 38 cooperates with the notches to keep the clamping arms and the locking element 15 in locked relation.

From the foregoing description it is evident that an extremely simple mop holder is provided, which may be manufactured at a relatively low cost and sold at a correspondingly reduced cost. It is further manifest that an exceedingly simple and inexpensive clamping lock and hinge arrangement is provided to releasably lock the parts in associated relation, and in which the lock cannot be accidentally moved to release the parts during the period in which the mop is used, or, in fact, at any time unless the parts are manually released.

It is further manifest that a simple and inexpensive hinge arrangement is provided which permits the swinging clamping arm to rotate in a plane longitudinal of the mop stick, and which allows the ready clamping and unclamping of the mop.

Having thus described the invention, what I claim and desire to cover by Letters Patent is:

In a mop holder, the combination of a means for engaging and holding a mop, said means including a fixed clamping arm and a movable clamping arm, said arms being hingedly connected together, an end of one of the arms being formed to provide the knuckle of the hinge and an end of the other of said arms being formed to provide the pintle of the hinge, and a pivoted locking ring adapted to maintain the other ends of said clamping arms in locked relation, the pivot of said locking ring being disposed so that a portion of said locking ring is arranged at one side of the pivot when arranged in locked relation to hold said locking ring against release.

In witness whereof, I hereunto subscribe my name this 27th day of March, A. D. 1922.

AUGUST J. HANKE.
